UNITED STATES PATENT OFFICE.

CHARLES A. CAMPBELL, OF NEW YORK, N. Y.

GAS-LAMP.

1,188,038.

Specification of Letters Patent. Patented June 20, 1916.

Application filed December 3, 1914. Serial No. 875,229.

To all whom it may concern:

Be it known that I, CHARLES A. CAMPBELL, a citizen of the United States, and a resident of Brooklyn, in the borough of Queens, city and State of New York, have invented 5 certain new and useful Improvements in Gas-Lamps, of which the following is a description in such full, clear, and exact terms as will enable any person skilled in the art to which it pertains to make and use the 10 same.

My invention relates to an improvement in inverted incandescent gas lamps the object of which is to simplify the construction 15 of such lamps and thereby render them less expensive to produce and more certain and durable in operation.

It is also an object of my invention to construct an incandescent gas lamp which, 20 as such, will be as perfect as possible and which will yet simulate closely the well known indirect electric light fixture, now very extensively employed for indoor lighting, in which the light is thrown upward 25 against the ceiling and sometimes shaded at the under side.

To this end the invention consists in certain novel features of construction and combination of elements which will be fully set 30 forth hereinafter and particularly pointed out in the claims.

The accompanying drawings illustrate as 35 an example the preferred form of the invention.

In these drawings—Figure 1 is a central vertical section of the lamp. Fig. 2 is a sectional plan on the line 2—2 of Fig. 1. Fig. 3 is a detail sectional plan on the line 3—3 of Fig. 1. Fig. 4 is a detail elevation of 40 the gas cock operating arm. Fig. 5 is a detail of the lock pawls of the gas cock with parts in section on the line 5—5 of Fig. 2 and Fig. 6 is a detail section of the gas cock on the line 6—6 of Fig. 2.

The lamp is supported from the ceiling 45 or other supplying part by a gas pipe 10 which carries the metal canopy 11 serving to protect the ceiling from the heat. The pipe 10 is fastened into a lateral or three-part fitting 12 preferably of cast metal which in turn has its central portion fastened to a central bar 14 forming part of the rigid frame work of the lamp and preferably integral with the cast metal burner chamber 50 or box 15. This box 15 is formed with an

interior partition 15^a producing two compartments, the function of which will be hereinafter pointed out and from the box arms 16 radiate to an integral band 17. These have sockets 17^a in which other radial 60 arms 18 are fastened and these extend to the encircling band or belt 19 and are secured to it by screws 20 or other means.

The structure above outlined forms the rigid frame of the lamp and all parts of 65 the lamp are mounted on and supported by said frame. In addition the parts 12 and 15 serve certain functions in the operation of the lamp which will be described in their order. The band 19 sustains a casing or 70 globe section 21 which is preferably of glass and is contracted at its top to carry a mounted crown 22 of metal. The globe 21 is open at its top to exhaust the products of combustion. At its lower edge the band 19 75 carries, by the usual screws 23, an imperforate globe 24 which envelops the whole bottom of the lamp. This arrangement of the two globes, one at the top and one at the bottom, with the band 19 surrounding 80 the lamp between them, gives the before mentioned indirect electric light effect and if one or both of the globes are opaque (as they usually are) the casual observer will not recognize the lamp as gas operated. 85

The three part fitting 12 is tubular as shown, the tubular arm passing off laterally and downwardly from the pipe 10 and carrying at its lower end a tube 25 which extends to the nipple 26 of the Bunsen casting. 90 This Bunsen casting has manifold parts which are illustrated in Figs. 1, 2, and 3. The nipple 26 communicates with the casing 27 of the cock plug 28 controlling the gas flow to the two branches 29. As shown in 95 Fig. 6 the plug 28 has a three-way passage and when in the position shown in that view opens both branches 29 to the gas supply, but if turned one quarter revolution will open one branch to the exclusion of the 100 other according to the extent of rotation of the plug.

As shown best in Figs. 1 and 4 the plug 28 has a four toothed ratchet 30 fastened on its stem outside of the band 19, the stem extending through the band for this purpose. Mounted loosely on the stem of the plug is an arm 31 one end of which is weighted and the other furnished with an operating chain. This arm carries a dog 31^a coating 110

with the ratchet, whereby the plug 28 may be given a progressive step-by-step rotation. 32 indicates a beveled dog which coacts with teeth 33 on the plug 28 and prevents back 5 return motion of the plug. 34 indicates a stop arm on the Bunsen casting to limit the stroke of the arm 31. Therefore, it will appear that by pulling on the operating chain the plug 28 may be turned to cut off 10 all gas supply to the branches 29 or to supply gas to either branch to the exclusion of the other.

The branches 29 terminate in inward bends 35 which carry the gas checks or regulators comprising constriction nipples 36 and needle valves 37, the latter extending outside of the branches and through the band 19 within easy reach of the operator. In this way the flow of gas through the 15 checks may be regulated. From the nipples 36 the gas jets pass into the Bunsen tubes 38, openings 39 being provided for the admission of atmospheric air to form the Bunsen mixture. The Bunsen tubes 38 are in two 20 sections (according to the specific structure shown) and the inner and major sections are cast integral with the box 15 and enter the same on opposite sides of the partition 15^a. In this manner the usual Bunsen mixture 25 may be supplied at will, in regulated proportions, to either or both chambers of the box 15.

The bottom of the box 15 on each side of the partition 15^a is formed with preferably 30 two orifices to accommodate the usual ceramic burner nipples 40 producing with the mantles 41 four inverted incandescent lights which may be operated simultaneously or in groups of two according to the adjustment 35 of the plug 28. A pilot light is provided by carrying inward a tubular extension 42 from the nipple 26 and fitting said extension with a pilot tube 43 which discharges under the box 15 so that when the mixture is turned 40 on the constantly burning pilot flame will ignite the gas mixture and start the operation of the lamp. This pilot flame burns continuously unaffected by the cock-plug 28 and is regulated by a separate needle valve 44 seated 45 in the extension 42. The band 17 may be fitted with a skirt 45 to collect the air supply which enters through the open top of the globe 21; and 46 represents a metal stack or intensifier to accelerate the draft 50 of air through the lamp.

The operation and method of using my invention will be apparent to those skilled in the art from the foregoing description.

It will be noted that my invention provides for a most durable form of construction which insures the reliable operation of the lamp under all conditions of hard service particularly out of doors and in other exposed places. It further provides for 60 the easy adjustment and repair of all of the

parts and by locating the regulating and Bunsen forming devices to one side they are protected from the heat and consequent destruction and may be reached for adjustment while the lamp is in operation.

Having thus described my invention what I claim as new and desire to secure by Letters Patent is:

1. A gas lamp having a mixing chamber to supply the burners, the chamber divided 75 into two compartments, separate Bunsen forming devices respectively feeding said compartments, a gas supply, a three way cock controlling the gas movement to the Bunsen forming devices and burner mouth 80 pieces adapted to carry mantles for each of the said compartments of the said chamber.

2. A gas lamp having a mixing chamber divided into two compartments, separate burner mouth pieces adapted to carry mantles 85 respectively communicating with said compartments, separate Bunsen forming devices respectively communicating with said compartments and means for admitting the supply to one or both of said compartments. 90

3. A gas lamp having a mixing chamber divided into two non-communicating compartments, each with a separate burner mouth piece, separate juxtaposed Bunsen forming devices leading respectively to the 95 said compartments, a three-way gas cock for opening either or both of said Bunsen forming devices to their respective compartments and separate means on each burner mouth piece for carrying separate mantles under 100 the same.

4. A gas lamp having a mixing chamber, burner mouth pieces at its underside, a gas supply pipe above the mixing chamber and from which the mixing chamber is supported, an elbow passing sidewise from the gas supply pipe, a gas pipe extending downward from the elbow, an annular frame member joined to the mixing chamber, a Bunsen forming device carried by the frame member and communicating with mixing chamber and an intensifier tube supported on said annular frame member, the downward extending gas pipe passing outside of the intensifier.

5. A gas lamp having a mixing chamber divided into two compartments, burner mouth pieces respectively for said compartments, Bunsen tubes respectively leading to the compartments of the chamber, Bunsen forming device for said tubes, gas supply means to the Bunsen forming devices, means for opening either or both of the Bunsen forming devices to the gas supply, an annular frame member rigid with the Bunsen tubes and mixing chamber and an exterior band supported from said frame member and surrounding the Bunsen forming device and mixing chamber and adapted to carry a globe section.

6. A gas lamp having a mixing chamber divided into two compartments, inverted burner devices respectively for each compartment, Bunsen tubes respectively leading 5 into the compartments of the mixing chamber, an encircling frame member surrounding the mixing chamber and joined thereto and to the Bunsen tubes, globe supporting means joined to the frame member, complementary Bunsen forming devices communi-
10

cating with the Bunsen tubes and means for controlling the gas supply to either or both of said Bunsen forming devices.

In testimony whereof I have hereunto signed my name in the presence of two wit- 15 nesses.

CHARLES A. CAMPBELL.
